SPARK PLUG

Lloyd McKinsey Field, Cleveland, Ohio

Application February 6, 1934, Serial No. 709,962

7 Claims. (Cl. 123—169)

This invention relates to spark plugs, and more particularly to spark plugs of the valve type for receiving air.

The main object of the invention is to provide a spark plug of said character, which admits outside air and thereby the electrodes and other exposed parts are kept clean of carbon and also cooled.

Another object of the invention is to provide a spark plug of said character, in which the valve is of special design and light in weight and therefore quick and positive in action.

A further object of the invention is to provide a spark plug of said character, which consists of few parts, is simple in construction and inexpensive to manufacture.

For a clear understanding of the invention, the same will be hereinafter fully described with reference to the accompanying drawing, and the novel features thereof will be particularly pointed out in the appended claims.

In the drawing, Figure 1 is a longitudinal sectional view of a spark plug constructed in accordance with my invention.

Fig. 2 is a similar view, on an enlarged scale, of the lower part of the insulator and valve structure.

Fig. 3 is a transverse sectional view, taken on line 3—3 of Fig. 2, and

Fig. 4 is a bottom plan view of the disc valve.

Referring to the drawing, 1 represents the metallic shell, 2 the porcelain insulator, and 3 the gland nut for retaining the insulator in the shell. The shell is threaded at 4 for attachment into the cylinder of an internal combustion engine, and is provided with a shoulder at 5 for supporting the insulator 2. The lower end of the insulator preferably terminates short of the shell. A suitable gasket 7 is employed at 5 and another gasket 8 between the upper shoulder 9 of the insulator and the retaining nut 3.

The insulator 2 is provided with a longitudinal opening 10, which is reduced in diameter at its lower end, as indicated at 11, thereby forming an annular shoulder 12, and is enlarged and internally threaded at its upper end as indicated at 13. Arranged in the opening 11 of the insulator is a nipple 14 having an enlarged head 15 of substantially the same diameter as the opening 10 and forming an annular shoulder 16 which is adapted to engage the shoulder 12 of the insulator. The head 15 of the nipple 14 is rounding or dome shaped at 17 and flat on top as indicated at 18.

The nipple 14 depends below the lower end of the insulator 2 and shell 1 and serves as a part of the

center electrode. Said member 14 is provided with a central opening 19 which extends from its flat top 17 through its lower or outer end. The shell electrode is indicated by 20. Fixed in the opening 10 of the insulator 2 is a tubular member 21 by means of threads at 22 corresponding to the threads at 13, and the lower end of said member engages the head 15 of the nipple 14, thereby forming the other part of the center electrode. The opening at the lower end of the tubular member 21 above the head 15 of the nipple 14 is enlarged to provide a chamber 23 for a check valve 24. The valve 24 is a comparatively thin disc of slightly less diameter than the chamber 23 and having a shallow conical face 25, which is adapted to engage the seat 26 of the chamber 23 for closing the tubular member 21 against exit from the cylinder of the engine. The disc valve is provided with a recess 27 across its lower flat face 28, which normally rests against or upon the flat top 18 of the nipple 14, and establishes communication through the tubular member 21 and said nipple to permit the inflow of air. By making the check valve 24 of the disc type, the air or gas has a broad area on which to act. The tubular member 21 projects above the insulator 2 and is threaded at 29 for receiving a suitable nut 30 for attachment of the electric circuit wires.

In practice, the disc valve 24 normally rests upon or against the top 18 of the nipple 14. Upon the down stroke of the engine piston, cool outside air is drawn in through the tubular member 21, chamber 23, around the valve 24 and by way of its recess 27 to the opening 19 of the nipple, and strikes the shell electrode 20 with intensified force due to the contracted opening of said nipple, thereby not only cleaning said electrode of carbon but cooling same and also the spark plug itself. Upon the up or compression stroke of the piston, the valve 24 is forced quickly and positively against its seat 26 thereby closing the tubular member 21 and preventing loss of pressure in the cylinder.

From the drawing and description, it is seen that this spark plug cooled and the electrode thereof both cooled and cleaned by the intensified inflow of outside air, and that the light disc check valve acts quickly and positively to prevent loss of compression or to admit the outside air upon the intake stroke of the piston.

It will be understood that slight changes in the details of construction may be made within the scope of the claims.

Having fully described my invention, what I claim is:

1. A spark plug comprising a shell, an insulator retained within the shell, a tubular electrode in the insulator, a valve arranged within said electrode, and said valve being a disc.
- 5 2. A spark plug comprising a shell, an insulator retained within the shell, a tubular electrode in the insulator, a valve arranged within said electrode, and said valve being a thin disc of light weight.
- 10 3. A spark plug comprising a shell, an insulator retained within the shell, the insulator having a longitudinal opening, a nipple in and supported by the insulator, a tubular member in the insulator in contact with the nipple, and a valve adapted to close said tubular member under compression.
- 15 4. A spark plug comprising a shell, an insulator retained within the shell, the insulator having a longitudinal opening, a nipple in and supported by the insulator, a tubular member in the insulator, in contact with the nipple, the tubular member adjacent the nipple being provided with a chamber, and a valve in the chamber adapted to permit air to be drawn through said member and said nipple but close said member against compression.
- 20 5. A spark plug comprising a shell, an insulator retained within the shell, the insulator having a longitudinal opening, a nipple in the insu-
- lator, a tubular member in the insulator in contact with said nipple, the tubular member adjacent said nipple being provided with a chamber, a disc valve in the chamber, and the valve having one face adapted to close said member and another face provided with means for permitting inflow of air from said member through said nipple.
- 25 6. A spark plug comprising a shell, an insulator retained within the shell, the insulator having a longitudinal opening, a nipple in the insulator, a tubular member in the insulator in contact with said nipple, the tubular member adjacent said nipple being provided with a chamber, the chamber having a seat, a disc valve in the chamber, the valve having a face adapted to engage said seat and an opposite face adapted to engage said nipple, and the last mentioned face of said valve having a transverse recess adapted to permit communication from said chamber through said nipple.
7. A spark plug comprising a shell, an insulator retained within the shell, the insulator having a longitudinal opening, the insulator having an annular shoulder, a nipple, the nipple being supported by said shoulder, a tubular member in the insulator and in contact with and pressing said nipple against said shoulder, and a valve adapted to close said tubular member.
